UNITED STATES PATENT OFFICE.

JAMES C. SERGESON, OF PHILADELPHIA, PENNSYLVANIA; ALLAN M. SERGENSON, EXECUTOR OF SAID JAMES C. SERGESON, DECEASED, ASSIGNEE TO STANLEY C. SERGESON, OF PHILADELPHIA, PENNSYLVANIA.

SHUTTLE.

Application filed November 24, 1922. Serial No. 602,950.

To all whom it may concern:

Be it known that I, JAMES C. SERGESON, a citizen of the United States, residing in the city and county of Philadelphia, State of Pennsylvania, have invented a new and useful Shuttle, of which the following is a specification.

My invention consists of a shuttle for a loom in which provision is made for doubly locking the bobbin, and so effectively preventing its improper release from the spindle of the shuttle, and also preventing improper opening motion of the spindle.

To this end there are employed a plurality of catches which are engageable with the bobbin at different places thereon, novel means for retaining both catches on the bobbin during the operation of the shuttle, and novel means for releasing both catches from the bobbin when the latter is to be removed.

The invention is satisfactorily illustrated in the accompanying drawing, but the important instrumentalities thereof may be varied, and so it is to be understood that the invention is not limited to the specific details shown and described, as long as they are within the scope of the claims.

Figure 1 represents a top plan view of portion of a shuttle embodying my invention.

Figure 2 represents a partial side elevation, and a longitudinal section thereof on line 2—2. Figure 1, the parts being in the operative position of the shuttle.

Figure 3 represents a bottom plan view.

Figure 4 represents a view similar to Figure 2, showing, however, different positions of parts due to the spindle being opened or thrown out.

Similar numerals of reference indicate corresponding parts in the figures.

Referring to the drawings:

1 designates a portion of the body of a shuttle which in general respects is of usual construction.

2 designates a spindle which carries the bobbin 3, said spindle having its inner end connected with the head 4 which is mounted in the body 1 by the pivot pin 5 as the axis of said head and consequently of said spindle.

6 designates a catch which is provided with ears 7 which are mounted on one side

of the head 4, said catch having on an end 55 towards the bobbin the inturned tongue 8 which is adapted to enter the circumferential groove 9 on the adjacent end of the bobbin for holding the latter in operative position, the heel end of said catch having 60 bearing against it the spring 10 which is seated in a recess in the head 4 and serves to retain the tongue 8 engaged in the groove 9.

12 designates a catch which is provided with ears 13 which are mounted on the side of the head 4 opposite to the catch 6, said catch 12, having on an end towards the bobbin the inturned tongue 14 which is adapted to enter the groove 9 on the bobbin 70 for holding the latter in operative position, the heel end of said catch 12 having bearing against it the spring 15 which is seated in a recess in the head 4 and serves to retain the tongue 14 engaged in said groove 9. 75

It will now be seen that the bobbin is held in an operative position on the spindle and consequently in the body of the shuttle by a plurality of catches which are mounted on the head 4, as has been stated.

The end portion of the catch 12 is formed with an elbow 16 forward of which is the transversely extending deflecting pin 17 which is secured within the adjacent portion of the body 1 of the shuttle, it being noticed that the terminal limb 18 of said elbow is extended outwardly from the main length of the catch 12.

19 designates a knuckle which is composed of a plate having projecting therefrom towards the head 4, the angular lips 20 and 21, leaving between them the recess 22. The lip 21 has its outer end rounded and seated in the recess 22 on the adjacent portion of the head 4 forming an axis which permits the knuckle to rock on said head. On the back of the knuckle is the stem 23 which is encircled by the spring 24 which bears against said knuckle and is seated on the base of the recess 25 in the interior of the nose portion of the body of the shuttle, the pressure of said spring on the knuckle retaining the latter in engagement with the head 4 while permitting said knuckle to rock on said head in the movements of the spindle 2. 95 100 105

The portion of the head 4 below the knuckle is formed with the depending limb 26 which is adapted to abut the adjacent

wall of the body 1 as a stop 30 to limit the closing of the spindle and holds the head firmly in position during the operation of the shuttle.

5 It will be seen that when the spindle is closed or in operative position the bobbin will be engaged by the catches at different places and so doubly locked on the spindle whereby the bobbin cannot be withdrawn 10 from the latter, the head 4 now being controlled by said knuckle and rendered immovable in the locked positions of the catches on the bobbin as will be apparent on reference to Figure 2.

15 When the bobbin is to be removed the spindle is thrown up as in Figure 4. Then the head 4 turns on its axis with the spindle whereby the knuckle 19 fulcrumed on the said head by the lip 21 is turned downwardly and the catch 6 carried by said head is raised whereby its heel end is in the path of the upper lip 20 of the knuckle which lip is moved forwardly by the knuckle and so said end enters the recess 22 of the latter 20 and it is pressed downwardly by said lip 20. This raises the end of the catch that has the tongue 8 thereon, see Figure 4, and so said tongue is removed from the groove 9 of the bobbin and the bobbin is no longer 25 held by said catch. Simultaneously therewith the lower catch 12 is carried up by the head 4 whereby the elbow 16 is advanced to the pin 17 and then rides upon the latter when the terminal limb 18 being offset from the main length of the catch is placed also 30 on said pin and rides thereon so as to press said limb 18 towards the head 4 and as a consequence deflect the end of the catch 12 that has thereon the lip 14 from the bobbin 35 and so said lip is removed from the bobbin, thus unlocking the latter. The head 4 is now controlled by said knuckle in the unlocked position of said catches, as apparent 40 in Figure 4, and the catches are retained in 45 said unlocked position.

As both catches are now disconnected from the groove in the bobbin the latter is unlocked and so may be slipped from the spindle and consequently entirely removed there- 50 of.

This will be apparent in Figure 4, the bobbin, however, having been removed therefrom. On replacing a bobbin and throwing down the spindle the catches are released of

the knuckles and deflecting pin respectively 55 and restored to the normal positions when both catches are interlocked with the bobbin in normal position as before stated and shown in Figure 2.

Having thus described my invention what 60 I claim as new and desire to secure by Letters Patent is:—

1. In a shuttle, a bobbin holding spindle, a pivotal head with which said spindle is connected, a plurality of catches mounted on said head adapted to engage the bobbin at different places thereon to retain it in operative position, and a knuckle adjacent to the head adapted to be fulcrumed thereon and adapted to engage one of said catches to remove the latter from the bobbin, and an abutment member in the shuttle adapted to engage the other catch to release the bobbin and permit it to be removed from the spindle. 70

2. In a shuttle, a bobbin holding spindle, a pivotal head with which said spindle is connected, a catch mounted on said head adapted to engage the bobbin and retain it in operative position, a rocking knuckle operatively arranged with respect to said head, and an abutment member in the shuttle, said catch having therein an elbow which is adapted to ride on said member when the spindle is raised and thereby remove said catch from the bobbin and release the bobbin whereby it may be removed from the spindle said head being adapted to cooperate with said knuckle to retain said catch in its unlocked position. 80

3. In a shuttle, a bobbin holding spindle, a pivotal head with which said spindle is connected, a plurality of catches mounted on said head adapted to engage the bobbin, an abutment member in the body, one of said catches having thereon an elbow which is adapted to ride on said member when the spindle is raised, said catch having a depending limb which is adapted to engage said abutment to open said catch, a rocking 100 knuckle operatively arranged with respect to said head whereby said head is controlled in the locked and unlocked positions of said plurality of catches, the body having therein a stop with which said limb is adapted to 105 abut serving to limit the motion of said head in the closed positions of the catches.

JAMES C. SERGESON.
